ARM SUPPORT

Donald F. Simmons, Seattle, Wash.

Application November 25, 1947, Serial No. 787,913

5 Claims. (Cl. 27—21)

1

This invention relates to arm supports, and it has reference more particularly to an arm support that is designed especially for use by embalmers; it being the principal object of the invention to provide a novel, practical and durable device for supporting the arms of a corpse, while on an operating table, in a position that is most practical and satisfactory for the embalming operation and which also will hold the arms in the natural and usually desired position until the body has set under the action of the embalming fluid or by reason of rigor mortis.

For a better understanding of my invention, it will here be explained that in the embalming of a human body, it is usual that the body be placed upon an operating table designed for this purpose, and that the arms be folded across the breast and supported there by the placing of blocks underneath the elbows at the side of the body. The embalming operation requires that certain blood vessels be opened up in the upper arms and neck to permit the blood to flow out under the forced injection of the embalming fluid. The use of blocks under the elbows, as the means for support of the arms, has not been entirely satisfactory due to the fact that they are usually in the way of the operator; they become stained and are hard to keep clean and they do not provide the stability of support or the adjustability that is a desirable feature.

In view of the above, and for various other reasons, it has been a further object of the invention to provide an arm supporting means that may be applied upon and directly across the body and which is so shaped that it will retain its position on the body and will support the arms against movement relative to the body and across the breast in the desired manner.

Yet another object of the invention is to provide an adjustable support that can be easily and readily adjusted to adapt it to bodies of different size.

Still further objects reside in the details of construction and combination of parts and in their combination and mode of use as will hereinafter be fully described.

In accomplishing these and other objects of the invention, I have provided the improved details of construction, the preferred forms of which are illustrated in the accompanying drawings, wherein—

Fig. 1 is a perspective view illustrating the functional use of an arm support embodied by the present invention.

2

Fig. 2 is a side or edge view of the same, indicating its adjustability.

Fig. 3 is a top or plan view of the support.

Fig. 4 is a cross section on line 4—4 in Fig. 3.

Fig. 5 is a cross section on line 5—5 in Fig. 3.

Referring more in detail to the drawings—

Briefly described, the arm supporting means of this invention comprises a cross bar that is designed to be disposed transversely of and to rest upon the chest or breast of the body with which it is used, and which has its opposite end portions shaped to provide seats or rests upon which the arms may be placed for support. The bar is shaped to conform to the upwardly rounded form of the body and is adjustable in length to best adapt it to the size of the body.

The support is designated in its entirety by reference numeral 10, and as shown best in Fig. 2, it comprises paired, or what may be referred to

as complementary opposite end portions 10a and 10b which are disposed with inner end portions overlapped and adjustably joined. Each of the parts is made up from a flat strip or strap of metal; the strip being approximately fifteen inches long, one and three-fourths inches wide and about three-sixteenths of an inch thick. Preferably stainless steel would be employed but any other suitable material might be used with the same results, and the kind of material used is not critical.

The part 10a, which is the top member as the device is applied in use, is formed along its inner end portion with a longitudinal row of spaced holes 12, and at its inner end has flanges 13—13 at opposite sides that are bent downwardly and inwardly about the opposite side edges of the underlying member as a guide and holder for retaining the relationship of parts. At its inner end, the underlying member is formed with an upwardly turned stud 16 adapted to be located in any one of the holes 12 to establish and retain the adjustment that may be made for any particular body.

The outer end portions of the paired members 10a and 10b are slightly upwardly turned and thus provide seats or rests as designated at 18—18 against which the arms are rested for support.

With the device so constructed, it is used as follows: Assuming the body is resting on the operating table, the bar or support 10 is placed upon and across the chest at a location just above the level of the elbows. The proper adjustment is made to extend or reduce the length of the bar to accommodate the body, by unscrewing the stud on the lower member from the hole

in the overlying member and then the parts are adjusted endwise as required and the stud then seated in the appropriate hole. Then the arms are laid, respectively, on the rests 18 at opposite ends of the bar and the forearms crossed across the chest as shown in Fig. 1. Since the stud is on the under member, there is no tendency under the weight of the arms for the parts to become disengaged.

The device so applied will hold the arms up, out of the way of drainage and at the natural and desired position. Also, the device is readily adapted to bodies of different size, is easy to apply or remove and overcomes the many objections to the use of blocks or other forms of supports 15 that are applied against the table. The device may be easily cleaned and kept sterile.

Having thus described my invention, what I claim as new therein and desire to secure by Letters Patent is:

1. An arm support of the character described comprising a flat bar adapted to be disposed upon and transversely across a body, and having an upwardly arched medial portion to conform to the body shape and having its opposite end portions extended to opposite sides of the body and upwardly curved at their ends to provide upwardly facing seats for the resting of the arms of the body therein.

2. An arm support of the character described comprising a flat bar adapted to be disposed upon and transversely across a body, and having an upwardly arched medial portion to conform to the body shape and having its opposite end portions extended to opposite sides of the body and upwardly curved at their ends to provide upwardly facing seats for the resting of the arms of the body therein, said bar comprising opposite end members, with inner end portions thereof overlapped and adjustably assembled together for changing the effective length of the bar between the arm seat portions.

3. An arm support of the character described comprising a flat bar adapted to be disposed upon and transversely across a body, and having an upwardly arched medial portion to conform to the body shape and having its opposite end portions extended to opposite sides of the body and upwardly curved at their ends to provide up-

wardly facing seats for the resting of the arms of the body therein, said bar comprising complementary opposite end members of flat, strip material, with their inner end portions flatly overlapped and slidably joined together for adjustment of distance between the arm seats, and means for retaining the members at their different positions of adjustment.

4. An arm support of the character described comprising a flat bar, adapted to be disposed for support upon and transversely across a body, with opposite end portions thereof extended beyond opposite sides of the body and providing arm rests; said bar being symmetrically upwardly arched along its medial portion to conform to the body shape; said flat bar comprising complementary opposite end members, disposed with their inner end portions flatly overlapped one upon the other; the inner end portion of the overlying member being formed with a longitudinal row of spaced holes, and at its inner end having a sliding connection with the underlying portion for a telescopic adjustment of the length of the bar; said underlying portion being formed at its inner end with a projecting stud adapted, by endwise adjustment of the members, to be selectively applied to any one of the holes in the overlying member to hold the members in adjusted relationship.

5. A support as recited in claim 4 wherein the said arm rests of the bar are formed by upwardly curving the outer end portions of the bar members and wherein the sliding connection of the inner end of the overlying section with the underlying section is provided by means of flanges in the overlying member that are bent so as to extend beneath the side edges of the underlying member.
